No. 745,020.

PATENTED NOV. 24, 1903.

W. B. LEECRAFT.
TROLLEY CONTROLLER.
APPLICATION FILED JAN. 31, 1903.

NO MODEL.

UNITED STATES PATENT OFFICE.

WALTER B. LEECRAFT, OF DENISON, TEXAS.

TROLLEY-CONTROLLER.

SPECIFICATION forming part of Letters Patent No. 745,020, dated November 24, 1903.

Application filed January 31, 1903. Serial No. 141,283. (No model.)

To all whom it may concern:

Be it known that I, WALTER BENJAMIN LEECRAFT, a resident of Denison, in the county of Grayson and State of Texas, have invented 5 certain new and useful Improvements in Trolley-Controllers, of which the following is a specification.

This invention has for its nature means operating to pull down the trolley-pole of an electric car when its trolley jumps the conductor-wire.

Broadly stated, the invention consists of peculiar means involving novel and improved details of construction and arrangement of parts which operate to instantly pull down the trolley-pole when its trolley jumps the conductor-wire.

The invention consists, further, in utilizing air, gas, or fluid under pressure in connection with peculiar automatic means operating, when the trolley jumps from the conductor-wire, to pull down the trolley-pole and hold it down.

The invention consists, further, in providing an automatic signal worked by the controller mechanism for notifying the conductor or motorman that the trolley is out of proper contact with the conductor-wire along the track.

30 In order to enable others to make and use my invention, I will now proceed to describe it in detail with reference to the accompanying drawings, forming a part of this specification.

35 In the drawings, Figure 1 is an end view of a trolley-car, showing my invention in use. Fig. 2 is a view showing my invention detached and enlarged with the cylinder in vertical section, and Fig. 3 shows an enlarged detail sectional view of my improved valve.

In carrying out my invention I employ a cylinder A, supported at upright position, substantially as shown, or by any suitable means.

40 B indicates a suitable piston having an expansion-spring B' on its piston-rod B². The spring just mentioned is confined between the piston B and the upper detachable end A' of the cylinder A.

45 At or near the upper end of the piston-rod B², I provide a circular or disk-shaped flange B³, which may have its outer edge B⁴ inclined,

as shown, adapted for locking engagement with a suitable yielding catch C, having a handle C' or other means by which it may be worked. The engaging end of the catch C may be inclined at C', as shown. The piston-rod is suitably packed at A², where it passes through the end A' of the cylinder.

With the upper end of the piston-rod B², I connect one end of a cord D or other flexible member having its other end extended several times around a drum E on the shaft F, which latter may be supported by suitable uprights F', though obviously simple brackets extending down from the car-roof would answer and serve the same end.

E' indicates a drum of greater diameter than the drum E, which may be in one piece with the smaller drum and fixedly connected therewith. D' indicates a cord with one end extending several times around the drum E', but wound thereon in opposite direction to the cord on the drum E. The upper end of the cord D' is secured to the trolley-arm, as will be understood.

In Fig. 1 of my drawings I show the ordinary trolley-cord D³, which I do not claim, though it is used in connection with my invention for replacing the trolley.

G denotes a suitable whistle or alarm sounded by air-pressure when the piston is forced down below its connecting air-passage G', as will appear farther on.

H indicates a suitable valve-chest, which may be integral with the cylinder A or secured thereto, as found expedient.

I indicates a suitable tube connecting in open communication with the upper ends of the interior space of the cylinder A and the valve-chest H, as shown. J indicates a similar tube providing open communication between the lower end of the cylinder A and the lower inner space of the valve-chest H, as shown.

K indicates a tube connecting the inner space of the valve-chest H, as shown, which may extend from some storage-tank on the car containing air, gas, or other fluid under pressure or have suitable connection with a fluid-car-brake system. The lower end of the valve-chest H is closed by a screw-plug L, having an adjusting-screw L', and the object of which is to adjust the tension of an expan-

sion-spring M, which latter serves to yieldingly hold the piston-valve N to the upper end of the valve-chest, as more clearly shown in Fig. 3. The upper end of the spring M rests against a suitable spider O, fixed to the under side of the piston-valve. Its lower end rests upon a plate O' within the recess O² of the screw-plug L. With the parts just described obviously the tension of the spring may be suitably adjusted for proper working of the piston-valve N. It will be noticed that the piston N has a vertical passage N', having at its upper end a downwardly-seating valve P, which is normally held unseated by an expansion-spring P' on its stem P². This spring is confined on the stem P² between the valve P and the spider O, as shown. The valve-stem P² extends down through the spider and has on its lower end one or more adjusting-nuts P³. It will be further noticed that the lower end of the valve-stem P² extends into the upper end of the ring M and that this end of the spring is kept centered by a suitable boss on the lower side of the spider O.

The operation of my improved trolley-controller is as follows: When the trolley-wheel jumps from the conductor-wire, the trolley-arm will fly upwardly with drawing and unwinding action of the cord D' from the drum E'. The drum E being fixedly connected with the drum E' it will wind up the cord D and at the same time through its connection effect a quick upward movement of the piston B against tension of its spring B'. This upward movement of the piston B will compress air in the upper end of the cylinder A and the tube I, adapted to seat the valve P against its spring P' and also force down the piston-valve past the inlet-opening of the tube K. This action effects free communication from the tube K through the valve-chest and tube I into the upper end of the cylinder A in rear of the piston B. Now obviously the stored pressure just stated will force the piston down in the cylinder A and at the same time through its connecting parts draw down the trolley-pole. On the downward movement of the piston N when it passes the whistle the latter will be sounded, and thereby notify the conductor or motorman that the trolley has jumped from the conductor-wire. According to my invention the piston B is forced down in the cylinder A to and past the inlet-opening of the lower end of the tube J. Now obviously when the piston B has passed the lower open end of the tube J the air-pressure on both sides of the piston-valve N will be balanced, leaving the spring M free to force the piston-valve to cut off pressure from the storage-tank or brake system, as the source of power may be. I have hereinbefore referred to a circular disk or flange B³ on the upper end of the piston-rod P² and stated that its use is for locking engagement with a catch C on the upper end of the cylinder A. According to my invention the disk or flange B³

is located on the piston-rod B², adapted for locking engagement with the catch C when the piston B reaches the end of its downward movement. In the locking action just described the inclined under surface or edge B⁴ of the flange or disk comes in contact with the inclined end C² of the catch. This action takes place just before the piston B passes the inlet or lower end of the tube J. Continued downward movement of the piston to the end of its stroke will effect to push back the yielding catch, and when the piston has reached the end of its stroke the catch will spring to locking position over the top of the flange. In this position of the parts the trolley-pole is held down by the catch C and connecting parts against upward pulling strain of the trolley-spring. It will be noticed that a spring B' is arranged on the piston-rod. The object of this spring is to yieldingly check pulling action of the trolley-spring. It will be further noticed that I provide a vent-hole S in the cylinder A near its lower end. The object of this vent is to allow free circulation of air into and out of the cylinder as the piston moves slowly up and down, according to variations in height of the conductor-wire. During slow up-and-down movement of the piston B, just stated, air on either side thereof has free circulation through the valve-chest and communicating tubes, since the valve P is held elevated above its seat by the spring P', whose tension will yield only to excessive air-pressure that would be produced upon rapid upward movement of the piston B. When the trolley is released from its locked-down position, it may be guided back onto the conductor-wire by aid of the cord D'.

Having thus described my invention, what I claim as new, and desire to secure by Letters Patent, is—

1. In a trolley-controller of the character described, the combination of a cylinder-piston and piston-rod, connecting means extending from the piston-rod to the trolley-pole, a valve-chest having open communication with both ends of the said cylinder, a yielding piston-valve within the valve-chest having a vertical passage therethrough, a yielding normally open valve automatically operating to close the said passage through the piston-valve, a tube leading into the valve-chest from a supply of air under pressure as specified, with the supply of air normally cut off by the said piston-valve, and an alarm device adapted to be sounded upon quick movement of the piston, substantially as described.

2. In a trolley-controller of the character described employing a cylinder-piston and a piston-rod and also means connecting the piston-rod to the trolley-pole, a valve-chest having open communication with both ends of the said cylinder, a piston-valve within the valve-chest yieldingly supported at one end of its movement, a passage through the said piston-valve, a yielding normally open valve

- adapted upon excessive pressure to close the passage through the said piston-valve, a tube supplying air under pressure to the said valve-chest normally closed against passage of air by the said piston-valve, a flange on the piston-rod, as specified, and an automatic catch adapted for locking engagement with the said flange as the piston reaches the end of its inward stroke, substantially as described.
10. 3. In combination with a trolley-controller of the character described employing air under pressure and a cylinder-piston and piston-rod with the latter in operative connection with the trolley-pole, a valve-chest having open communication with both ends of the said cylinder, means adapted to supply air under pressure to the valve-chest, a valve in the said chest normally cutting off the supply of air under pressure, a spring serving to yieldingly support the said valve at its normal closing position, means adapted for adjusting the tension of the said spring, and a passage through the said cut-off valve with means whereby it may be closed by excessive pressure produced at one end of the cylinder substantially as described.
4. In a trolley-controller of the character described, employing air-pressure-power means normally inactive when the trolley is in place on the conductor-wire, the combination therewith of a yielding cut-off in the said power means, consisting of a piston-valve having a passage through it normally open, but adapted to be closed by excessive pressure of air exerted, through and by suitable connecting mechanism, when the trolley leaves the conductor-wire substantially as described.
5. In a compressed-air trolley-controller, means operating to draw down the trolley-pole when the trolley jumps from the conductor-wire, automatic locking means adapted to catch and hold the trolley pulled down, an automatic alarm adapted to indicate that the trolley has jumped from the conductor-wire, and automatic means whereby compressed air is supplied by quick action of the piston and adapted to be cut off by slow action thereof, substantially as described.
6. In a trolley-controller operating to pull down the trolley-pole when the trolley leaves the conductor-wire, a normally inactive piston in operative connection with the trolley-pole, means for conveying air under pressure to the said piston, closed by a valve adapted to be opened by air-pressure exerted by the said piston when the trolley leaves the conductor-wire, and automatic means whereby the trolley is held pulled down, substantially as described.
7. The combination in a trolley-controller employing compressed air and mechanism operated thereby which is normally inactive but adapted to be worked by quick action of the trolley-pole through suitable connecting and intermediate means, a suitable casing with connecting tubing and a piston-valve, the latter having a passage therethrough normally open but adapted to be closed by excessive pressure produced on one side of the piston-valve when the trolley jumps its conductor-wire substantially as described.
8. In a trolley-controller and in combination, an upright cylinder, a fixed catch, a piston in the cylinder having means at the upper end of its rod adapted for locking engagement with said fixed catch, when the piston reaches substantially the limit of its downward stroke, a cord extending from the upper end of the piston-rod passing around, and fixed, to a rotatable drum, a larger drum fixed to the latter and having flexible connection with the trolley-pole, a suitable casing having open communication with both ends of the said cylinder, a tube extending from some supply of compressed air, a yielding piston-valve within the said casing normally serving to cut off the said supply of compressed air, a passage through the piston-valve normally open but adapted to be closed by excessive pressure of air produced in the upper end of the cylinder upon quick action imparted to the said piston when the trolley jumps its conductor-wire substantially as described.
